COMBINED TELEPHONE HANDSET AND STAND

Lionel W. Mosing, Springfield, N.J., assignor to Bell Telephone Laboratories, Incorporated, New York, N.Y., a corporation of New York

Filed May 11, 1960, Ser. No. 60,537

Term of patent 14 years

(Cl. D26—14)

FIG. 1

FIG. 2

Fig. 1 is a perspective view of a combined telephone handset and stand showing my new design with the handset in place on the stand and the stand positioned for use on a horizontal surface; and

Fig. 2 is a perspective view thereof with the handset removed from the stand and the stand positioned for use on a vertical surface.

The handset and the stand are each symmetrical about their respective longitudinal axes, and the opposite sides are the same as the sides shown. The essential features of my new design reside in the portions shown in full lines.

I claim:

The ornamental design for a combined telephone handset and stand, substantially as shown and described.
